UNITED STATES PATENT OFFICE.

WILLIAM F. ZIMMERMANN, OF MAPLEWOOD, NEW JERSEY, ASSIGNOR TO GOULD & EBERHARDT, OF NEWARK, NEW JERSEY, A CORPORATION OF NEW JERSEY.

RAIL CLAMP WITH CONCENTRATED CONTROL.

Application filed March 5, 1926. Serial No. 92,562.

Shaping machines, as commonly constructed, comprise a frame, a tool carrying ram horizontally movable on the frame, a cross-rail vertically adjustable on the frame 5 and a work-table horizontally adjustable lengthwise of the rail and transverse to the direction of movement of the ram. The cross-rail is usually secured to the frame by means of two clamps, one located at each 10 side of the shaper frame, and which are manually operated from opposite sides of the machine.

In the operation of these machine tools it frequently becomes necessary to change 15 the elevation of the work-table. This adjustment is effected by means of a suitable elevating screw which has a threaded connection with a nut carried by the cross rail, thus by effecting relative rotation between 20 the screw and nut the cross rail, and the work-table carried thereby, may be adjusted vertically. However, before this adjustment may be made it is necessary that the operator release the rail clamps at both sides 25 of the machine and after the desired adjustment is effected the clamps must again be tightened. In most shapers the actuating crank for the elevating mechanism is located at the side of the machine where the 30 operator normally stands during the operation of the machine. To change the elevation of the work-table in a shaper so constructed, the operator first releases the clamp on his side of the machine and then 35 walks around the machine and releases the other clamp. He then returns to his original position and actuates the elevating mechanism. After having secured the desired setting of the cross-rail he sets the 40 clamp on his side of the machine, again walks around the machine and sets the other clamp and returns to his original position, having necessarily walked around the machine twice in effecting the adjustment. 45 Certain other shapers have the shaft for the rail-elevating crank located at the far side of the machine. In these machines the operator effects the adjustment of the rail while at the far side of the machine and sets 50 the clamp at that side before returning to his original position thereby reducing his journeys by one, but even in this latter type

of machine it is necessary that the operator go to the far side of the machine at least once in effecting an adjustment of the table. 55

There is a growing demand by present day manufacturers for machine tools which save the time and energy of the operator and which may be operated entirely from a single position, inasmuch as his 60 walking about to effect adjustments, etc. not only consumes considerable time but it also distracts his attention from his work which results in a considerable loss in efficiency and production. This invention therefore 65 has for an object to provide simple and efficient means for actuating both of the rail clamps of a shaper from the operator's side thereof, thereby eliminating the necessity of his walking around the machine in effecting 70 a vertical adjustment of the work-table.

Heretofore in certain machine tools attempts have been made to actuate spaced clamps by means of a single clamp-actuating shaft operatively connected to clamps located at opposite sides of the machines, so that rotation of the shaft will simultaneously actuate both clamps. It has been found, however, that it is practically impossible so to keep the clamps adjusted that they will 80 both tighten at exactly the same time and that therefore one clamp will usually tighten ahead of the other thereby stopping rotation of the shaft and precluding complete tightening of the looser clamp. 85

To overcome this condition equalizing devices were embodied in the clamp-actuating means but this resulted in complicated constructions which were costly to build. Also these prior devices included power multiplying connections and occasionally an operator would apply too great power therefo with the result that parts of the clamp actuating means would be either broken or strained. 90

This invention proposes a clamping means for shaper rails by means of which each clamp may be actuated independently of the other from the operator's side of the machine and which is devoid of equalizing means and power multiplying connections. 95

Another object of this invention is to provide simple and efficient means whereby the operator may, without moving from his normal working position, actuate, individually 100

and in any desired order, a plurality of segregated clamps of which at least one is located remote from the operator.

While this invention is shown and described in connection with shapers, to which it is particularly adaptable, it is perceived that it might also be used to advantage in other types of machine tools and such other uses are contemplated.

10 Other objects and advantages will be in part indicated in the following description and in part rendered apparent therefrom in connection with the annexed drawings.

To enable others skilled in the art so fully 15 to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:—

Fig. 1 is a side elevation of a portion of a shaper embodying the present invention.

25 Fig. 2 is an enlarged horizontal section on the line *a*—*a* of Fig. 1, and Fig. 3 is a vertical section on the line *b*—*b* of Fig. 1.

Referring more specifically to the drawings the invention is disclosed as embodied 30 in a shaper comprising a main frame 1 provided, at its upper end, with suitable guide-ways within which is slidably mounted, for horizontal reciprocation, a ram 2 carrying the usual tool *t*. The ram is reciprocated 35 back and forth by conventional mechanism which forms no part of this invention and which therefore is designated generally as 3. Beneath the ram there is located the usual work-table 4 adapted to support the work to 40 be acted on by the cutting tool. This work-table is supported primarily by, and is horizontally adjustable on, a cross-rail 5 fitted to vertically disposed guideways 6 and 7 located at opposite sides of the main frame 1.

45 The cross-rail and its attached work-table are adapted to be shifted vertically on the main frame to vary the position of the work with respect to the tool. This adjustment is effected by means of a screw 8 having a 50 threaded engagement with a suitable nut carried by the cross rail whereby relative rotation between the nut and screw shifts the rail and table vertically. Inasmuch as the table elevating means forms no part of the

55 present invention detailed illustration and description thereof is deemed unnecessary. It is believed that, for the purpose of this disclosure, it will suffice to say that the relative rotation between the nut and screw is effected by means of a shaft 9 journaled 60 lengthwise of the rail and formed at the operator's side of the machine with a squared end adapted to receive a suitable wrench or crank 90 by means of which the operator

may rotate the shaft and thereby effect vertical adjustment of the table.

The desired setting of the table having been obtained, it is then necessary that the rail be securely locked to the main frame to preclude any movement of the parts during 70 the cutting operation. This locking is effected by clamps *c* and *d*, located at opposite sides of the main frame, which serve to draw the finished faces 5^a and 5^b of the rail tightly against the vertical guide-ways 6 and 7 provided by the main frame. These clamps consist respectively of straps 10 and 11 engaging finished surfaces or guideways 12 and 13, of heavy vertically disposed flanges 14 and 15 provided by the main frame. Each of 80 these flanges is slotted vertically as at 16 to permit free passage of suitable clamp-adjusting and clamp-actuating bolts later to be described. The straps 10 and 11 and the rail 5 are maintained in sliding contact with the 85 flanges 14 and 15 by bolts 17 (shown in Fig. 1 only) passing through apertures in the straps, through the slots 16 in the frame, and threaded into the cross rail. These bolts maintain the parts freely shiftable and prevent the table and rail from tipping forwardly when the clamps are released.

Clamping of the rail to the frame is effected by draw-bolts 18 and 19 located, respectively, at the operator's side of the machine and at the side remote therefrom. The bolt 18 forming a part of the clamp *c* passes freely through an aperture 20 in the strap 10, then through the slot 16 in the flange 14 and is threaded into the rail at 21. The head 18^b 100 of the bolt 18 is seated against the strap 10 and is readily accessible to the operator when standing in his normal working position at the right side of the machine shown in Fig. 1 and therefore he may, at any time, apply a 105 suitable wrench thereto to loosen or tighten that clamp without changing his position.

The clamp *d* at the opposite side of the machine is the one that heretofore has made it necessary for the operator to walk around the machine to effect its release and reclamping. This invention provides simple and efficient means by the employment of which the operator may just as readily actuate the remote clamp without leaving his operative 110 position as he may actuate the clamp *c*. This improved clamp actuating means comprises a shaft 22 journaled lengthwise of the cross rail in bearings 23 and 24 and formed at the operator's side of the machine with a hexagonal head 25 similar in shape and size to the head 18^b of the bolt 18, whereby it may be rotated by the same wrench utilized to turn the bolt 18. The bolt 19, forming a part of the clamp *d*, passes freely through 115 an aperture in the strap 11, through the slot 16 in the flange 15, and then through an unthreaded bore 26 in the cross rail. Upon the

inner end of the bolt 19 is threaded a nut 27 having its periphery formed as a worm-wheel with which meshes a worm 28 cut on the shaft 22. A collar 29 pinned to the bolt 5 prevents the nut 27 from being unthreaded from its bolt. The shaft 22 is held against axial movement by collars 30 and 31 pinned thereto and engaging opposite walls of the bearings 23 and 24 therefore rotation of the 10 shaft will, through the worm and worm-gear, likewise effect rotation of the nut 27. This nut bears against a boss 32 on the rail 5 and is thereby held against moving inwardly on the bolt 19. The resultant effect is that 15 the bolt 19 is moved axially toward the shaft 22. This axial movement of the bolt 19 causes its head 19^b forcibly to engage the strap 11 thereby drawing it against the face 13 of the flange 15 simultaneously with like 20 engagement of the face 5^b of the rail with the guide 7 provided by the main frame, thus the rail will be firmly clamped to the frame without any tendency to bend either the rail or the frame. The head 19^b is preferably 25 adjustable relative to the bolt 19 to effect an initial setting of the clamp so that it may be tightened or released by only slight rotation of the shaft 22. A jam-nut 33 threaded on the bolt 19 behind the head 19^b 30 serves to maintain the head in its adjusted positions. A key 34, set into the bolt 19, has its projecting edge fitted into a way 35 formed in the strap 11 and serves to hold the bolt against rotation but permits it to move 35 axially under the action of the nut 27.

From the foregoing it will be perceived that this invention provides simple and efficient means whereby the operator selectively and individually and with a single wrench 40 may actuate both of the rail clamps of a shaper without moving from his operative position at the machine.

Without further analysis, the foregoing will so fully reveal the gist of this invention that others can, by applying current knowledge, readily adapt it for various utilizations by retaining one or more of the features that, from the standpoint of the prior art, fairly constitute essential characteristics 50 of either the generic or specific aspects of this invention and, therefor, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:—

60 1. A shaper combining an upright frame; a cross-rail vertically adjustable on the frame; two independent clamps located at opposite sides of the frame each acting independently to secure the rail to the frame in its adjusted positions; means comprising

a clamping bolt located at the operator's side of the machine to actuate the clamp at that side of the machine; a clamping bolt embodied in the clamp at the other side of the machine and remote from the operator; 70 and a clamp actuating means extending from said remote clamping bolt to the operator's side of the machine to enable him to actuate said remote clamp from his normal working position. 75

2. A shaper combining a frame; a rail adjustably mounted on the frame; means including a lever located at one side of said machine for effecting vertical adjustment of said rail on said frame; a clamp located at 80 said side of the frame for securing the rail to the frame; a clamp located at the opposite side of the machine for securing said rail in its adjusted positions; means to actuate said clamp from the side of the machine where the adjusting lever is located, said means including a shaft rotatably but non-translatably journaled in said rail; and an operative connection between said shaft and said clamp whereby the latter is actuated by rotary motion of the former. 85

3. A shaper combining a frame; a rail adjustably mounted on the frame; a single clamp at each side of said frame to secure the rail to the frame; means to actuate said clamps each independently of the other from one side of the machine, one of said clamp actuating means comprising a bolt passing freely through one of said elements and threaded into the other; means permitting a wrench to be engaged with said bolt to cause it to be rotated thereby to draw said members into frictional contact; a bolt passing freely through both said frame and rail adjacent the other clamp; a clamping nut 95 threaded on said last named bolt; a shaft extending lengthwise of said rail and terminating at the side of the machine where said first mentioned clamp is located; means permitting a shaft actuating element to be 100 secured to said shaft; and a gear connection between said shaft and said nut whereby actuation of said shaft rotates said nut and operates the last mentioned clamp. 105

4. A shaping machine combining a frame provided at its opposite sides with vertically arranged guideways; a cross-rail vertically adjustable on said guideways; two independent clamp devices located at opposite sides of the machine, each adapted to secure 110 said cross-rail to one of said guideways; individual clamp actuating means readily accessible to the operator from one side of the machine to enable him selectively to actuate said clamp devices; one of said clamp actuating devices comprising a manually actuatable shaft journaled in said cross-rail and extending to the remote clamp, said shaft being formed adjacent the operator to receive an actuating element; a clamp actuat- 115 120 125 130

ing bolt; and an operative connection between said shaft and said bolt to cause said bolt to be moved axially thereby to actuate said last named clamp when said shaft is actuated.

5. A shaper combining a frame; a cross rail vertically adjustable thereon; clamping devices located at opposite sides of the shaper for clamping the rail to the frame;

and individual means for selectively actuating said devices, one of which extends to the remote side of the machine from the operator when in his normal working position to actuate the clamp at that side. 10

In witness whereof, I have hereunto subscribed my name. 15

WILLIAM F. ZIMMERMANN.
